UNITED STATES PATENT OFFICE

EMANUEL V. WENDELL, OF CHICAGO, ILLINOIS.

DESIGN FOR A WATCH-CASE.

SPECIFICATION forming part of Design No. 17,433, dated July 5, 1887.

Application filed April 25, 1887. Serial No. 236,089. Term of patent 7 years.

To all whom it may concern:

Be it known that I, EMANUEL V. WENDELL, of Chicago, in the county of Cook and State of Illinois, have invented and produced a new and original Design for Watch-Cases, of which the following is a specification, reference being had to the accompanying drawings, forming a part thereof, in which—

Figure 1 is a side elevation of my newly-
10 designed case, and Fig. 2 is a like view of a
modification thereof.

Like letters of reference indicate like parts
in the different figures.

The leading feature of my design consists in
15 forming the center or frame of the case in the
form or configuration of a horseshoe, within
the contour of which the outlines of the lids,
whether round or otherwise when viewed in
elevation, may fall.

20 In the drawings, A represents the center of

the case, the general contour of which is in the
form of a horseshoe, while B indicates the lids,
which are preferably circular in outline; but,
if desired, they may be made to conform to the
general contour of the center, as shown in Fig. 25
2. A projecting part, A', of the center, hav-
ing scallops a a, is formed to indicate a web,
filling out the space between the parts repre-
senting the projecting ends of the shoe.

What I claim, and desire to secure by Let- 30
ters Patent, is—

The design for a watch case, the same con-
sisting of a case the contour of which is in the
form of a horseshoe, having the part A' and
scallop a a between the depending ends, sub- 35
stantially as shown and described.

EMANUEL V. WENDELL.
